US00D876394S

(12) **United States Design Patent** (10) **Patent No.:** **US D876,394 S**
(45) **Date of Patent:** **** Feb. 25, 2020**

(54) **AUDIO COMPONENT**

(71) Applicant: **Harman International Industries, Incorporated**, Northridge, CA (US)
(72) Inventors: **Tim Nugent**, Santa Monica, CA (US); **Andy Flint**, Santa Clarita, CA (US)
(73) Assignee: **Harman International Industries, Incorporated**, Northridge, CA (US)
(**) Term: **15 Years**
(21) Appl. No.: **29/626,795**
(22) Filed: **Nov. 20, 2017**

Related U.S. Application Data

(62) Division of application No. 29/551,703, filed on Jan. 15, 2016, now Pat. No. Des. 827,608.

CLAIM

The ornamental design for an audio component, as shown and described.

DESCRIPTION

FIG. 1 is a perspective view of an audio component showing our new design;

FIG. 2 is an opposite perspective view thereof;

FIG. 3 is a front elevational view thereof;

FIG. 4 is a side elevational view thereof, the opposite side elevational view being a mirror image thereof;

FIG. 5 is a rear elevational view thereof;

FIG. 6 is a top plan view thereof; and,

FIG. 7 is a bottom plan view thereof.

The broken lines are used to illustrate unclaimed portions of the invention and form no part of the claimed design.

1 Claim, 3 Drawing Sheets
